(57) **CLAIM**

The ornamental design for a valve assembly as shown and described.

DESCRIPTION

FIG. 1 is a top perspective view of a valve assembly, according to the present design.

FIG. 2 is a front elevation view of the valve assembly of FIG. 1.

FIG. 3 is a rear elevation view of the valve assembly of FIG. 1.

FIG. 4 is a right-side elevation view of the valve assembly of FIG. 1.

FIG. 5 is a left-side elevation view of the valve assembly of FIG. 1.

FIG. 6 is a top plan view of the valve assembly of FIG. 1; and,

FIG. 7 is a bottom plan view of the valve assembly of FIG. 1.

The broken lines shown in the drawings depict portions of the valve assembly that form no part of the claimed design.
